United States Patent Office.

HENRY CROSSLEY, OF BROOKLYN, NEW YORK.

Letters Patent No. 80,923, dated August 11, 1868.

IMPROVEMENT IN LUBRICATORS.

The Schedule referred to in these Letters Patent and making part of the same.

TO ALL WHOM IT MAY CONCERN:

Be it known that I, HENRY CROSSLEY, of the city of Brooklyn, county of Kings, and State of New York, have invented a new and improved Mode of Constructing Oil-Cups for Steam-Cylinders, &c.; and I do hereby declare that the following is a full and exact description thereof, reference being had to the accompanying drawings, and to the letters of reference marked thereon.

The nature of my invention consists in constructing the upper valve of oil-cups, that are intended to be used against pressure, with a top or cover, that has passed through its centre a valve-stem, the valve being at the lower end, and the upper end secured by a bolt, allowing it to revolve freely within the cover. The valve-seat is made of a metal that is sufficiently soft to receive the impression of the valve. The screw of the cover answers the double purpose of securing the cover and compressing the valve.

To enable others skilled in the art to make and use my invention, I will proceed to describe its construction and operation.

I construct an oil-cup in the usual manner, with a globe-valve at the lower end, as shown in the accompanying drawings, marked A A. I combine the upper valve with the cover, producing better results, and of a less expense than those heretofore devised and used. The cover and hand-wheel B B has passed through its centre the valve-stem C, which is fitted so as to revolve. At the lower end is the valve D, which shoulders against the inside of the cover B B. The top of the stem is provided with a bolt, E, with a head large enough to keep it in its place and allow it to revolve.

The mouth of the cup is contracted, so as to allow a sufficient thickness of metal, as shown at F F, for the groove G, which contains an alloy of softer metal, and forms the valve-seat. The cover B B is provided with the usual screw, marked H, which answers the double purpose of securing the top and compressing the valve, while the valve being movable, it does not grind or cub the seat, but simply compresses it.

What I claim as my invention, and desire to secure by Letters Patent, is—

The oil-cup, having its upper valve combined with the cover, and the cover applied to the cup, all substantially as herein shown and described, and for the purposes set forth.

HENRY CROSSLEY.
